UNITED STATES PATENT OFFICE.

IVAN FOX, OF PHILADELPHIA, PENNSYLVANIA.

DESIGN FOR A BRIDGE OR SPRING FOR SPECTACLES, &c.

SPECIFICATION forming part of Design No. 29,697, dated November 22, 1898.

Application filed October 12, 1898. Serial No. 693,350. Term of patent 7 years.

To all whom it may concern:

Be it known that I, IVAN FOX, a citizen of the United States, residing in the city and county of Philadelphia, in the State of Pennsylvania, have invented and produced a new and original Design for Spectacle or Eyeglass Bridges or Springs, of which the following is a specification, reference being had to the accompanying drawings, forming part thereof.

10 Figure 1 is a view in end elevation, Figure 2 a view in perspective, and Figure 3 a top plan view, of a bridge or spring embodying my new design.

The leading or material feature of my design comprises the shape or configuration of the spring or bridge illustrated in the drawings, wherein as shown each of the extremities of the bridge or spring presents the form of a two-pronged fork, the points of which

diverge from their point of junction and separation to their outer ends, thus presenting a V-shaped opening.

The bridge or spring is designated A and the respective fork members a.

Having thus described my invention, what I claim as new, and desire to secure by Letters Patent, is—

The design for a bridge or spring for spectacles or eyeglasses, as herein shown and described.

In testimony that I claim the foregoing as my invention I have hereunto signed my name this 3d day of October, A. D. 1898.

IVAN FOX.

In presence of—

F. NORMAN DIXON,
THOS. K. LANCASTER.
